UNITED STATES PATENT OFFICE.

JOHN M. WENZEL, OF CHICAGO, ILLINOIS.

SIGNALING DEVICE.

Application filed June 3, 1922. Serial No. 565,622.

To all whom it may concern:

Be it known that I, JOHN M. WENZEL, a citizen of Germany, residing at Chicago, in the county of Cook and State of Illinois, have invented new and useful Improvements in Signaling Devices, of which the following is a specification.

This invention relates to electrically operated door releasers for apartment houses whereby it is made possible to release the main entrance door of the house from any one of the apartments without the occupants thereof leaving the same and going to the door to unlatch it.

The invention has for its object to provide an apparatus of the kind stated, a signal device which will indicate to the occupants of the apartments whether the releaser has properly functioned to effect release of the door, and whether the person at the door has gained entrance or not.

The object stated is attained by means of a combination and arrangement of parts to be hereinafter described and claimed, and in order that the same may be better understood, reference is had to the accompanying drawing, wherein the invention is illustrated diagrammatically.

Referring specifically to the drawing, 5 denotes the main entrance door of a building containing a number of apartments. This door is provided with an electrically operated releasing device whereby the door may be released from any one of the apartments without the occupants leaving the same and going to the door. This is a well known apparatus and hence a detailed description thereof is not necessary. It may be stated, however, that the door releasing mechanism is operated by an electro-magnet which is shown at 6. This magnet is interposed in an energizing circuit, and the current source may be a battery 7 or a transformer. One side of the current source is connected by a conductor 8 to one of the terminals of the magnet, and to the other terminal of the magnet is connected a conductor 9 which leads to a switch 10 located in the apartment remote from the door. 40 From this switch a conductor 11 leads to the other side of the current source. The switch may be of any preferred type, the conductor 9 being connected to the stationary contact 12, and the conductor 11 to the movable contact 13 of the switch. The circuit is normally open, and when it is closed

by operating the switch 10, the magnet 6 is energized, whereupon the release of the door 5 takes place, so that the person seeking entrance may open the same.

To the energizing circuit of the door releaser is connected a branch circuit in which is interposed a signal, such as a small lamp 14. One terminal of the lamp is wired to the conductor 8, as shown at 45, and the other terminal is wired, as shown at 46, to the contact 12 so as to be engageable also by the switch member 13. It will therefore be seen that both circuits are controlled by the switch 10.

The branch circuit in which the signal 14 is interposed is normally open at the switch 10, and it is also provided with a circuit closer which is controlled by the door 5. This circuit closer is a contact 18 adapted to bridge a gap in the line 45 when the door 5 is opened, said line having contacts 19 at the gap. When the door is closed, the electrical connection is broken. In the line 49, between the magnet 6 and the switch contact 12 is also a gap, with contacts 20, thereat, these contacts being opposite the contact 18. The contacts 19 are on one side of the contact 18, and the contacts 20 are on the opposite side. Thus, the contacts 19 and 20 are alternately engageable to the contact 18, the latter normally bridging the contacts 20. The contact 18 is in position to bridge the contacts 20 when the door 5 is closed, and it moves away from the contacts 20 to bridge the contacts 19 when the door opens.

The operation of the apparatus may be summarized as follows:

Upon closing of the switch 10, the blade 95 13 moves over into engagement with the contact 12. This closes the energizing circuit of the magnet 6, and the release of the door 5 takes place. When the door is opened, the circuit in which the signal 14 is interposed is also closed, and the signal is displayed as long as the switch 10 is held closed. The display of the signal 14 of course indicates to the occupant of the apartment that the door has opened, and that the door releaser has therefore properly functioned. A failure to obtain a signal is of course an indication that the door has not been opened. The door releaser circuit is broken and the device 6 is cut out 100 immediately the door opens, by the movement of the contact 18 off the contacts 20.

and over to the contacts 19. However the signal 14 continues to be displayed as long as the switch 10 is held closed and the contacts 18 and 19 touch. The apparatus therefore eliminates waste of electric current from unnecessary operation of the door releaser, and it is convenient and does away with all guess work as to whether the person at the door has gained entrance or not.

10 The drawing shows the switch and signal apparatus of one apartment only, but it will be understood that all the apartments of the building will be similarly equipped. The signal 14 need not be a light, but it

15 can be a bell, buzzer or any other electro-responsive signal device.

I claim:

1. The combination with an electrically operated door-releasing device, an energizing circuit therefor, and a controlling switch; of a branch circuit connected to said energizing circuit, and controlled by the aforesaid switch, and a signal device and a door-controlled circuit closer interposed in the branch circuit.
2. The combination with an electrically operated door-releasing device, and an energizing circuit therefor; of a branch circuit connected to said energizing circuit, a signal device and a door controlled circuit closer interposed in the branch circuit, a switch contact to which the branch circuit and one side of the energizing circuit are connected, and a movable switch member adapted to engage said contact, to which switch member the other side of the energizing circuit is connected.
3. The combination with an electrically operated door-releasing device, an energizing circuit therefor, and a controlling switch; of a branch circuit connected to said energizing circuit and controlled by the aforesaid switch, and a signal device and a door-controlled circuit closer interposed in

the branch circuit, said circuit closer being 45 operated by the opening of the door with which the releasing device is associated.

4. The combination with an electrically operated door-releasing device, an energizing circuit therefor, and a controlling switch; of a branch circuit connected to said energizing circuit, and controlled by the aforesaid switch, a signal device interposed in the branch circuit, and door-controlled circuit closers interposed in both 50 circuits and operating to close the branch circuit when the door opens, and simultaneously therewith to cut out the door-releasing device.

5. The combination with an electrically operated door-releasing device, and an energizing circuit therefor; of a branch circuit connected to said energizing circuit, a signal device interposed in the branch circuit, door-controlled circuit-closers interposed in both circuits and operating to close the branch circuit when the door opens, and simultaneously therewith to cut out the door-releasing device, a switch contact to which the branch circuit and one side of the 65 energizing circuit are connected, and a movable switch member adapted to engage said contact, to which switch member the other side of the energizing circuit is connected.

6. The combination with an electrically operated door-releasing device, an energizing circuit therefor, and a controlling switch; of a branch circuit connected to said energizing circuit, and controlled by the aforesaid switch, a signal device interposed 70 in the branch circuit, and door-controlled circuit closers for both circuits, and operating by the opening of the door to close the branch circuit, and simultaneously therewith to cut out the door-releasing device.

In testimony whereof I affix my signature.

JOHN M. WENZEL.
